by Oning & Hague Atty.

UNITED STATES PATENT OFFICE.

LEBBEUS J. SMAIL, OF COFFEE CREEK, MONTANA.

FRAME CONSTRUCTION FOR SURFACE CULTIVATORS.

Application filed November 8, 1921. Serial No. 513,832.

To all whom it may concern:

Be it known that I, LEBBEUS J. SMAIL, a citizen of the United States, and a resident of Coffee Creek, in the county of Fergus and State of Montana, have invented a certain new and useful Frame Construction for Surface Cultivators, of which the following is a specification.

The object of my invention is to provide a simple, durable and comparatively inexpensive mechanism which is especially adapted to till the soil for the purpose of preserving moisture and also for destroying weeds.

A further object is to provide a cultivator mechanism provided with a series of blades so arranged and carried by suitable mechanism in such a manner that the blades may be operated at a slight distance below the ground surface for the purpose of cutting all weeds which they engage, and also for the purpose of loosening the surface to form a mulch, the blades being so arranged that they may do a maximum amount of work with a minimum amount of sharpening and also may be drawn through the earth with a minimum amount of power.

A further object is to provide in a cultivating device having substantially horizontally arranged surface blades, improved means for mounting the blades so they may be made to automatically follow the irregularities of the earth surface to be cultivated.

These and other objects will be apparent to those skilled in the art.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is an isometrical view of my improved cultivating device.

Figure 2 is a rear elevation of the same showing how the device is adapted to follow uneven surfaces.

Figure 3 is a detail sectional plan view taken on the line 3—3 of Figure 1.

Figure 4 is a detail plan sectional view taken on the line 4—4 of Figure 1.

Figure 5 is a detail sectional view taken through one of the weeding blades showing the manner in which it enters the ground surface.

My improved device comprises a frame provided with an arch member having a horizontal member 10 and vertical members 11, the members 11 being held against movement relative to the member 10 by means of 60 braces 12.

Secured near the upper end of each of the members 11, I have provided a bracket 13 which extends rearwardly and is designed to receive a vertically arranged shaft 65 14 which extends downwardly having its lower end mounted in a bracket 15 secured adjacent to the outer face of the lower end of the member 11 by means of suitable rivets. The bracket 15 is also provided with 70 a downwardly extending portion 16 for the purpose of receiving a cutting blade 17.

Slidably and pivotally mounted on each of the shafts 14, between the members 13 and 15, I have provided a bracket 18 having 75 forked members 19 between which is mounted a wheel 20 by means of an axle 21. The bracket 18 is provided with a slot 22 which is designed to receive a bracket 23 slidably mounted on the shaft 14. The bracket 23 80 is pivotally mounted to a yoke 24 which extends upwardly at a point above the bracket 13, the said yoke being pivotally mounted to a lever 25 which is in turn pivoted to a bracket 26 mounted on the member 85 10. The bracket 26 is provided with a sector 27 which is engaged by the pawl 28 of the said lever 25, the said levers 25 extend toward each other and are substantially parallel with the member 10 and terminate at 90 a point substantially beneath each side of a seat 29 which is secured to a beam 30.

By this arrangement, it will be seen that by operating the lever 25, the bracket 23 may be slid upwardly and downwardly on 95 the shaft 14 and will cause the member 11 to be elevated or lowered.

Each of the members 11 is provided at its upper end with a brace bar 31. These brace bars extend forwardly and are secured 100 to the upper end of a vertically arranged bar 32. The upper end of said bar 32 is also secured to the forward end of the member 30. Auxiliary brace bars 33 are provided 105 which are secured to the upper end of the member 32 and near the central portion of the members 11. The lower end of the bar 32 is provided with a bracket 34 which terminates into a pointed shovel 35. This shovel is clearly shown in Figures 3 and 5. 110

Secured beneath the shovel 35, I have provided the forward end of the blades 17 which are also inclined and placed in an angular position relative to each other and 5 relative to the frame member 10, the blades 17 being designed to lie substantially horizontal with their cutting edges inclined downwardly and forwardly. A shaft 36 is mounted back of the member 32 and parallel 10 therewith by suitable brackets secured to the said member 32.

A wheel bracket 37 similar to the bracket 18 is slidably mounted on said shaft 36, the said bracket being operated by means of a 15 slide 38 pivotally secured to a yoke 39 similar to the yoke 24. The yoke 39 is pivotally connected to the forward end of a lever 40, said lever being pivoted to a bracket 41 mounted in the upper face of the member 20 30. The said bracket 41 is provided with a sector 42 which is for the purpose of locking the lever 40 in any desired position by means of a suitable pawl similar to the pawl 28.

25 Pivots secured to the forward edge of the bar 32, I have provided a hitch bar 43 having a series of openings 44, said openings being designed to receive a pin of a suitable clevis to which the draft bar of 30 any suitable power may be applied. The openings 44 provide means whereby the hitch may be raised or lowered to meet the requirements when the device is in operation under various conditions.

35 Secured near the bottom portion of the member 32, I have provided wing members 45 which are for the purpose of guiding weeds and drawing them to one side so as to not be wound in the wheel 46 mounted 40 in the bracket 37.

Secured to the lower end of each of the members 11, I have provided a guard 47 which is for the purpose of separating the cut weeds from the uncut weeds, this device being clearly shown in Figure 4 of the drawings.

By this arrangement, it will be seen that I have provided a triangular frame comprising the members 10, 11, 31, 32 and 33 and 50 also the blades 17. This frame is mounted on three wheels, the wheel 46 at a point behind the member 32 and the wheels 20 behind the members 11. Each of the said 55 wheels is adjustably mounted on the frame independent of each other so that the blades 17 may be made to assume any desired angle relative to the ground surface.

The operation of my improved weeder is substantially as follows:

60 The hitch may be applied to any one of the openings 44 to meet the requirements, depending on whether it is desired to run the point 35 shallow or deep. A tongue may be applied to the upper end of the member 65 43 if it is desired. This is of the usual con-

struction and is not shown in the drawings.

If the device is to be operated over comparatively level surface, the lever 40 is so adjusted that the point 35 will run beneath the ground surface the desired depth, while 70 the levers 25 are so adjusted that the back ends of the blades 17 will run substantially the same depth, if the device has a tendency to run out of the ground and the lever 40 is adjusted to permit the members 45 to 75 run a slightly greater depth than the back ends of blades 17. This will provide sufficient suction so that the blades will be held in the ground. As the machine is advanced, all weeds will be cut off below the 80 surface that fall within the path of the blades 17.

By arranging the wheel 46 behind the bar 32, it will be seen that the weeds are cut before they are run down by the said 85 wheel.

By mounting the blades in the manner as set forth and upon the triangular frame, it is possible for the blades 17 to operate over irregular surfaces, such as shown in 90 Figure 2.

If it is desired to cut the weeds on a ridge, the forward wheel 46 is run longitudinally with the crest of the ridge, while the wheels 20 will follow the inclined surface permitting the blades 17 to arrange themselves substantially parallel with the 95 surface.

If it is desired to cultivate or remove the weeds from a ditch or furrow, the shovel 35 is 100 moved longitudinally with the lowest part of the furrow and the blades 17 will assume the position shown in dotted lines in Figure 2.

If it is desired to move the cultivator from 105 one field to another, the levers 25 and 40 may be so operated that the blades 17 will be lifted above the ground surface. As clearly shown in Figure 5, the blades 17 are placed at an inclined position relative to the ground 110 surface, so that a suction is formed. When the said blades are forced beneath the ground, it will be seen that a certain amount of downward pressure is imparted to the said blades. This pressure may be carried 115 by the wheels 20 and 46, and thereby the draft of the device considerably lightened over what it would be if the downward pressure was carried by drag shoes such as is commonly used in devices of this kind.

120 Thus it will be seen that I have provided a cultivator which may be very effectively used for the purpose of killing weeds, or for the purpose of forming a mulch. It is my intention to build the machine in various sizes either for use with tractors or to be drawn by a team of horses, and further to be built so as to be drawn by a single horse and adapted to be operated between corn rows for cultivating corn after it is too big 125 130

to be cultivated with the regular cultivator. In laying corn by it is often the practice to hill the corn in the rows. This provides ridges of dirt in the rows and furrows between the rows. By my improved cultivator, it will be seen that the blades may be adjusted to follow these hills without being run deep enough to cut the roots of the corn.

I claim as my invention:

- 10 1. In a device of the class described, an arch member comprising a horizontal portion and downwardly extending portions, a V-shaped horizontally and forwardly extended frame member secured to the upper ends of the downwardly extending portions of said arch member, a downwardly extending member secured to the apex end of said V-shaped frame, a brace member extending from the apex end of said V-shaped frame member to the central portion of said arch, means provided on the lower end of each of said downwardly extending portions for connecting cutter blades, the downwardly extending portion of the apex end of said V-shaped member being provided with braces extending rearwardly to the downwardly extending portions of said arch member, the last said downwardly extending portions also being provided with braces connecting the horizontal portions of said arch member, two of the members for attaching the said cutters being provided with rearwardly extending portions having vertical openings, the upper end of each of the downwardly extending portions of said arch member being provided with rearwardly extending portions having vertical openings in

alignment with the openings of the rearwardly extending portion below for receiving a vertical shaft, the forward edge of the downwardly extending portion of the apex end of said V-shaped frame member being provided with a pair of forwardly extending portions, each of which is provided with a vertical opening, said openings being in alignment.

2. In combination, a horizontal V-shaped frame having at each corner a downwardly extending portion, means for connecting blades to the lower ends of said downwardly extending portions, caster wheels pivotally mounted to each of said downwardly extending portions, a lever device for independently raising and lowering each of said caster wheels relative to said downwardly extending portion, and a hitch pivotally connected to one of said downwardly extending portions.

3. In combination, a horizontal V-shaped frame having at each corner a downwardly extending portion, means for connecting blades to the lower ends of said downwardly extending portions, caster wheels pivotally mounted to each of said downwardly extending portions, a lever device for independently raising and lowering each of said caster wheels relative to said downwardly extending portion, a hitch pivotally connected to one of said downwardly extending portions, a seat mounted on said V-shaped frame, all of said levers being arranged so that their free ends are adjacent to said seat.

LEBBEUS J. SMAIL.
